UNITED STATES PATENT OFFICE.

JAMES DOUGLAS MACMAHON, OF NIAGARA FALLS, NEW YORK, ASSIGNOR TO THE MATHIESON ALKALI WORKS, OF NEW YORK, N. Y., A CORPORATION OF VIRGINIA.

APPARATUS FOR TRANSPORTATION AND UTILIZATION OF LIQUEFIED GASES.

Application filed January 6, 1925. Serial No. 833.

To all whom it may concern:

Be it known that I, JAMES DOUGLAS MACMAHON, a citizen of the United States, residing at Niagara Falls, in the county of Niagara, State of New York, have invented certain new and useful Improvements in Apparatus for Transportation and Utilization of Liquefied Gases; and I do hereby declare the following to be a full, clear, and exact description of the invention, such as will enable others skilled in the art to which it appertains, to make and use the same.

This invention relates to the utilization of liquefied gases, such, for instance, as liquid chlorine, and has to do more particularly with apparatus by which such gases may be readily transported in sealed containers under relatively high pressures, and rapidly withdrawn from these containers for use.

20 Gaseous products, such as chlorine, are commonly supplied to the consumer in containers in which the liquefied gas is under relatively heavy pressure. These containers are transported in railroad cars of different types, and in one form of car which has been highly satisfactory, the containers are mounted in cradles and the car has mains to which the container outlets may be connected so that the contents may be discharged without removing the containers from the car.

For many commercial purposes it is desirable to withdraw the gases from the containers in liquid form and each container is, therefore, provided with an outlet pipe the end of which lies near the bottom of the container. When the outlet is open the vapor pressure of the vaporized liquid in the container forces the liquid out through the outlet, and as the liquid level falls, further vaporization of the liquefied gas takes place. In such vaporization, however, a considerable quantity of heat is abstracted from the liquid and its temperature falls. If the rate of flow of the liquid is high, it will be impossible for the liquid within the container to absorb heat from the atmosphere in sufficient quantities to compensate for that used in the vaporization, and the vapor pressure in the container will, therefore, decrease and the flow of liquid will rapidly diminish. At ordinary atmospheric temperatures the liquid within the container can absorb the required quantity of heat so that the flow will be continuous, but when the

atmospheric temperature is quite low, as in winter, it is extremely difficult to secure a steady flow of liquid from the containers of any rapidity, and the discharge of the containers is so slow a process that it is frequently necessary to remove the containers from the car and place them within a heated building. This entails a considerable amount of handling of the containers, and the discharge of the contents is a slow and laborious process.

The present invention is intended to provide apparatus by which the contents of liquefied gas containers may be discharged rapidly while the containers are in place on the car, and is useful particularly when the containers are to be discharged at relatively low atmospheric temperatures. This invention involves the provision of a car on which a plurality of containers are mounted, together with associated apparatus by which the necessary heat may be transferred to the liquid in order to maintain the desired vapor pressure within the containers. By the use of this apparatus it is possible to discharge the containers separately and during the emptying of one container, one or more others may be suitably preheated so that the process of withdrawal may be carried on without interruption.

According to the present invention, a car is provided on which a series of containers are mounted in individual cradles. Extending lengthwise of the car, beneath these cradles are guide-ways or rails, in which may be placed a heating unit of appropriate form, which may be moved along the car from end to end. The heating unit preferably has a sufficient length so as to lie in heat-exchange relationship with a plurality of containers, and is suitably connected to a source of a heating medium. The unit is also provided with means by which it may be moved along the car. In addition to the heating unit the car is provided with an insulating covering which may be used to enclose a number of the containers, and as the containers are successively emptied the heating unit and covering are moved along the series of containers so that the liquid in each one in turn takes up heat radiated from the unit.

The car is preferably provided with mains to which the outlets of the containers may be connected, so that the operation of

emptying the containers is facilitated, and although it is preferable to discharge the contents from each container in turn, it is possible, with this arrangement, to empty 5 two or more simultaneously.

In the accompanying drawings I have illustrated one embodiment of the invention in the form which I now consider preferable, although it will be understood that 10 various other forms of apparatus may be used for the purpose, depending, to some extent, on the size of the containers and their arrangement on the car. In the present drawings the containers are of approximately 15 one-ton size, and are mounted in cradles extending transversely of the car. In these drawings,

Fig. 1 is a transverse section through the car showing a container in elevation,

20 Fig. 2 is a plan view of the car,

Fig. 3 is a plan view of one type of heating unit, and

Fig. 4 is a plan view of a detail of the car with the container removed.

25 Referring to the drawings, the car is illustrated somewhat diagrammatically but is of the type shown in Patent No. 1,458,588, issued June 12, 1923 to Max Mauran, which has proved very satisfactory. This car is 30 provided with an under-frame which consists of a central box girder 5 with suitable cross beams 6 distributed along the length of the car. Mounted on the under-frame at suitable intervals are cradles 7, each of 35 which has seats 8, 8, on which may rest a container 9. This container is a standard form and is of a size suitable to hold approximately one ton of liquid chlorine under 80 pounds pressure. At either end of 40 each cradle are clamping members 10, 10, having hooks 11, which engage the chime of the container.

45 Extending lengthwise of the car along the ends of the cross beams are running boards 12, with guard rails 13, and along one running board is mounted a main 14, which has intake valves 15, placed opposite each cradle. In one end of the containers are valves 16 and 17, the upper valve 16, 50 being provided with an outlet pipe 18, which extends nearly to the top of the container, while the valve 17 has an outlet pipe 19 which is turned downwardly and extends nearly to the bottom of the container.

55 When the contents of the container are to be withdrawn in gaseous form the valve 16 is connected by a pipe 20 to the valve 15 of the main, and when the contents are to be withdrawn in liquid form the lower 60 valve 17 is thus connected.

65 It will be noted that the container 9 as shown in Fig. 1, resting in its cradle, lies at some distance above the plane of the car surface, and extending the length of the car and lying in the depressed portion of

the cradle, are rails 21, which provide a track on which the heating unit may be placed. This unit 22, as shown in Fig. 3, takes the form of a pipe coil consisting of 70 headers and cross pipes and is provided at its ends with lugs 23, to which may be attached loops 24. This heating unit has a length equal to the distance between the centers of the first and third container, as shown in Fig. 2, and is provided with connections 25, 25, at one end. Through one of these connections the heating medium enters the unit and through the other, when steam is employed, the exhaust steam and 75 condensed water leaves the unit. The inlet connection is provided with a valve (not shown) so that the flow of the medium may be regulated.

When the car with the load of containers has been delivered at its destination and 80 placed near the main through which the contents are to be led to the point of consumption, the heating unit is placed under the container from which the contents are first to be withdrawn, and then connected 85 to the supply of heating medium. This container is then connected to the car main which has previously been connected to the conduit on the ground. A blanket 26 of suitable insulating material is now placed 90 in position over the container, beneath which the heater lies, and the heating medium is now passed through the heater. The 95 contents of the container may now be withdrawn at a comparatively high rate of flow, 100 until the container has been completely exhausted. As previously pointed out, the heating unit extends beneath a plurality of 105 containers and the insulating blanket is also sufficiently large to cover several containers. During the time that one of the containers is being discharged, the others are being 110 preheated. When the first container is empty, the outlets of the others are successively opened and the heater and blanket 115 are moved along the series. This procedure is carried on until all of the containers are empty and the containers may be emptied singly, or, if desired, two or more may be simultaneously connected to the main so 120 as to discharge the contents at the same time.

It will be seen that while the illustrated 125 apparatus is comparatively simple, it provides an efficient means of emptying the containers rapidly and at a minimum expense. The containers may remain on the car during discharge and, therefore, any handling is eliminated. Also, as the containers may be discharged rapidly, regardless of atmospheric temperature, no considerable delay is involved at the destination of the car. When the car is completely emptied, the heating unit and blanket may be removed 130 and used on another car.

While I have described the use of the apparatus in connection with the discharge of the contents of the containers in liquid form, it will be clear that this same type of apparatus is also useful when the gas within the containers is to be withdrawn in the gaseous form. For this purpose the upper outlet from the containers, the intake of which lies above the liquid level, will be connected to the main and as the gas is withdrawn the liquid within the container evaporates. The heating unit now supplies to the liquid the amount of heat required for the continuous vaporization of the liquefied gas, and the process is carried on until all the liquid has vaporized and has been withdrawn.

I claim:

1. The combination of a car having a series of containers for liquefied gas mounted thereon, each container having an outlet, the intake of which lies below the level of the liquid therein, a valve for controlling the rate of flow through the outlet, and a heating unit mounted on the car in heat exchange relationship to the containers and movable to different positions on the car.

2. The combination of a car having a series of cradles thereon, a container for liquefied gas seated in each cradle, an outlet in each container having an intake below the level of the liquid therein, a main extending along the car, connections between the outlets and the main, a valve in each outlet for controlling the rate of flow therethrough, and a heating unit mounted on the car and movable to different positions therealong, this unit being sufficiently large so that it may be placed in heat exchange relationship with a plurality of containers.

3. The combination of a car having a series of cradles disposed thereon, a con-

tainer for liquefied gases seated in each cradle, an outlet in each container having an intake below the level of the liquid therein, a main extending along the car, connections between the outlets of the main, a valve in each outlet for controlling the rate of flow therethrough, guideways on the car extending along the series of containers, a heating unit in the guideways and movable therealong, and connections for supplying a heating medium to this unit.

4. The combination of a car having a series of cradles disposed thereon, a container for liquefied gases seated in each cradle, an outlet in each container having an intake below the level of the liquid therein, a main extending along the car, connections between the outlets and the main, a valve in each outlet for controlling the rate of flow therethrough, a heating unit mounted on the car beneath the containers and movable to different positions on the car, this unit having a size sufficient to underlie a plurality of such containers, and an insulating blanket for enclosing the containers under which the heating unit lies.

5. The combination of a car having an under-frame, a plurality of cradles mounted on the frame, a container for liquefied gas seated in each cradle in spaced relation to the under-frame, an outlet from each container having an intake lying below the level of the liquid therein, guideways mounted on the cradles beneath the containers and extending throughout the length of the car, a heating unit in the guideways movable therealong, a main extending along the series of containers, connections between the outlets and the main, and valves in the connections for regulating the rate of flow therethrough.

In testimony whereof I affix my signature.
JAMES DOUGLAS MACMAHON.
